United States Patent Office

Des. 224,446
Patented July 25, 1972

224,446

HAND MAGNIFIER

John Orfei, North Revere, Mass., assignor to American
Science and Engineering, Inc., Cambridge, Mass.

Filed Oct. 13, 1969, Ser. No. 19,518

Term of patent 14 years

Int. Cl. D16—06

U.S. Cl. D57—1

FIG. 1

FIG. 2

FIG. 1 is a perspective view of a hand magnifier, showing my new design; and

FIG. 2 is a side view thereof.

The characteristic feature of my design resides in the specific configuration of the magnifier handle.

I claim:

The ornamental design for a hand magnifier, as shown and described.
